United States Patent

Des. 238,123

Patented Dec. 23, 1975

238,123

SHOE SOLE

Sumner F. Davis, Salem, N.H., assignor to Converse Rubber Company, a division of Eltra Corporation, Wilmington, Mass.

Filed May 28, 1974, Ser. No. 473,780

Term of patent 14 years

Int. Cl. D2—04

U.S. Cl. D2—320

FIG. 1

FIG. 2

FIG. 3

FIG. 4

FIG. 5

FIG. 6

FIG. 1 is a bottom plan view of a shoe sole showing my new design;

FIG. 2 is a side elevational view thereof;

FIG. 3 is an elevational view of the other side;

FIG. 4 is a top plan view;

FIG. 5 is an end view taken from the back of the shoe sole; and

FIG. 6 is a front end view.

I claim:

The ornamental design for a shoe sole, as shown and described.
